(57) **CLAIM**

The ornamental design for a display screen with moveable icons, as shown and described.

DESCRIPTION

FIG. 1 illustrates a front view of a first image in a sequence of a display screen with moveable icons, showing our claimed design; and,

FIG. 2 illustrates a front view of a second image thereof. The appearance of the animated image sequentially transitions between the images shown in FIGS. 1 and 2. The process of period in which one image transitions to another forms no part of the claimed design.

(Continued)

The broken lines illustrate portions of the display screen, and portions of the graphical user interface, and form no part of the claimed design.
